UNITED STATES PATENT OFFICE.

GEORGE W. RENZ, OF NEW YORK, N. Y., ASSIGNOR TO UNDERWOOD ELLIOTT FISHER COMPANY, OF NEW YORK, N. Y., A CORPORATION OF DELAWARE.

TYPEWRITING MACHINE.

Application filed December 3, 1927. Serial No. 237,363.

This invention relates to manifolding typewriting machines for continuous billing and other work where the carbons are held by their rear ends interleaved with the plies 5 of work-web, and periodically may be retracted for reuse in successive sections of the web.

The invention deals with double carbon-carriers employed when two work-webs or 10 groups of work-sheets for different purposes are to be used interchangeably. For such operation of the machine, there is provided a carbon-carrier composed of two superposed sets of carbon-blades. When 15 a lower web is to be written upon, the leading end of the upper web with its interleaved carbons is folded backwardly over the carbon-carrier at the rear of the machine and is kept in idleness. To render 20 this upper web active upon the platen, the leading end of the lower web in turn has to be disposed of by threading the same backwardly between said superposed sets of carbon-carriers, which threading operation 25 is usually tedious and painstaking to the unskilled operator.

According to the invention, the upper unit of carbon-carriers is hinged at the rear upon the lower unit and with a quick 30 throw may be swung up and backwardly beyond its vertical position to be held by a suitable stop. This affords ample space for convenient and quick handling of the lower web. The upper carrier then may be 35 restored to position the upper web for writing. In conjunction with this expedient, the invention provides means to prevent the carbon-holding blades upon the upper carrier from falling off the carrier when 40 the same is swung back in its extreme rearward position. The blades are arranged one in front of the other, upon steps descending towards the platen, and are fastened for quick detachment at one end by 45 plain pin-and-hole connections, and, furthermore, at the attached end provided with a finger-piece to handle the same. Preferably, a flat member is pivoted upon the carrier and normally set transversely of the 50 blades, so as to closely cover the finger-pieces to hold the blades down and in place upon the carrier. Said flat member may be swung out of the way to free the finger-pieces for detachment of the blades.

Other features and advantages will hereinafter appear.

In the accompanying drawings, Figure 1 is a sectional side elevation of a platen and platen-frame of a standard Underwood manifolding typewriting machine showing the relation between the double carbon-carrier and the platen, a lower group of work-sheets being in use while the upper group is idling.

Figure 2 is a view similar to Figure 1, 65 and showing the upper hinged part of the carbon-carrier thrown backwardly from Figure 1 position, and the lower web folded back to idle position, the intended action of the upper web being indicated in dot and dash.

Figure 3 is a detached perspective of the two hingedly interconnected and superposed carbon-carriers, and showing details of blade-arrangement, and the novel blade-se- 75 curing members.

Figure 4 is a partial top view upon the upper carbon-carrier, showing the pivoted blade-securing member swung sidewardly to ineffective position for detaching the carbon-blades.

Figure 5 is a detail perspective view with parts drawn apart and disclosing means for mounting said blade-securing member upon the carbon-carrier.

Figure 1 of the drawings illustrates the feeding of a multiple-ply web 10 on a standard Underwood continuous billing typewriting machine, and in addition shows another superposed web 11 idling upon the machine but ready for use, i. e., for substitution in place of the first-mentioned web.

The drawings show a web-feeding platen 12 having a platen-shaft 12^a and displaceably journaled upon a platen-frame, which 95 is substantially composed of side plates 13 connected by a usual paper-guide 14 extending at the rear of the platen and down around the platen. The platen-frame travels transversely of the machine in letter-feed 100 and return movement, and has a rearward extension 15 to serve as a track for the well-known carbon-carriage 16. More in detail, said track or frame includes a longitudinal rod or member 17 at either side and a front 105 18 and 18^a, said frame at its forward end being hinged to the paper-guide by means of bracket-plates 19,

which in turn are rigidly fastened to said paper-guide by means of clips 20. The rear end of the frame by means of rollers (not shown) has contact with a supporting rail 5 transversely mounted upon the machine-frame (not shown). The multiple-ply web 10 in Figure 1 is led from underneath the machine upwardly over a guide-bar 21 carried in standards 22 at the rear end of the 10 track, said guide-bar having usual settable gages 23 to laterally guide the paper, which then is conducted along the track to be passed over said aforementioned carbon-carriage 16 to be interleaved with carbons 15 16^a and thus be led around the lower part of the platen. The composite web is advanced around the platen with the aid of usual pressure-feed-rolls, indicated in dot and dash at 24, and is passed across the typ- 20 ing line indicated by a front-striking type-bar 25 to be delivered onto a collating table 25^a which carries attached thereto a usual settable leading edge gage 26. As the paper is advanced, the carbon-carriage through the 25 attached carbon-sheets is drawn forwardly until the writing of a certain section of the web is completed. In order to prepare a new section of the web for writing, the platen may be displaced in upward direction 30 so as to allow the web to be straightened out and the carbons under the control of said carbon-carriage to be redrawn between and relatively to the plies, which movement may be readily effected by pushing rearwardly 35 the well-known handle 27 (indicated in dot and dash) of said carbon-carriage. For upward displacement the platen-shaft has its bearings at either side at the end of rocking arms 28, which, in turn, by means of a rod 40 or axle 29, are mounted for movement in a vertical plane upon the platen-frame. With the leading edge of the web abutting the gage 26 and the carbon-carriage duly retracted, the platen may be restored to working 45 position and the written part of the web in the usual way may be severed from the pack by tearing the same across the sharp edge of a severing blade 30 which, located slightly above the typing line, is swingable 50 as a unit with the platen. The carbon-carriage 16 is of well-known standard construction and is substantially composed of a truck including a bed-plate 31 upon which are provided grooved rollers 32 to co-oper- 55 ate with flat rail-members 33, which are supported upon said longitudinal rods 17 to form the track-elements for the carbon-carriage. As may be seen from the drawings, the relative arrangement of said 60 grooved rollers and said flat rail-members is such as to prevent the truck from being lifted clear off the rails. The truck carries, however, detachably secured thereon a separate structure 33^a, including a base-plate 34 65 upon which is fixed at either side a block 35

formed with steps 36 descending towards the platen and which present the supporting faces for carbon blades or holders 36^a proper. As may be seen from Figures 3 and 4, there are provided in each step two holes 37 to 70 receive two corresponding pins provided at one end of a carbon-blade so as to rigidly locate the blade upon the carrier. A finger-piece 38 is provided upon each carbon-blade to handle the same. Means to locate and secure the detachable structure upon the truck (see Figure 1) include a pin 39 at either side depending from the base-plate and passing through holes provided in the truck bed-plate, and latches 40, each of which is 75 mounted upon the lower side of said truck bed-plate and which may engage in a kerf or slot provided in said pin 39. Said latch includes a flat body-member which is pivoted upon said bed-plate by screw 42 and has a 80 depending finger-piece 43 by which it may be swung sidewardly to release said slotted pin 39 and to allow said blade-supporting structure, as a whole, to be lifted off the truck. Two holes 43^a provided at one side 85 of the base-plate 34 and screws 44 serve to fasten said carbon-carriage handle 27 upon said base-plate. 90

The following part of the description is substantially concerned with attachments 95 and additions to the standard equipment which allow the convenient use of two interchangeable work-webs upon the carbon-carriage as mentioned above. To this end, there is provided a second carbon-blade carrier 44^a substantially a duplicate of the one described above. The structure 33^a which supports the lower blades 36^a and the second carbon-blade carrier 44^a are superposed upon each other and hingedly interconnected 100 at the rear so that the upper carrier may be swung backwardly, as illustrated in Figure 2. Said upper carrier, in particular, is formed with a stepped block 45 at either side, both blocks being interconnected by flat bar-members 46 to form a rigid unit and carrying carbon-blades as described above. Due to hinges 47 screwed at 48 and at 49 to the lower and upper carriers respectively, the upper carrier may be thrown from Figure 1 to Figure 2 position, which latter position is determined through the action of a link 50, which, at one end, is pivoted upon block 35 of said structure 33^a by screw 51, and, at the other end, has slot-and-screw 105 connection 52 with the upper carrier. Furthermore, regarding Figure 2, it will be seen that ample space is offered for withdrawing the lower web from the platen, and for folding the same back between the upper 110 and the lower set of carbon-blades to keep it out of the way when the upper carbon-blade carrier 44^a is restored for inserting the leading edges of the upper web under the platen and for a quick change from one 115 120 125 130

web to the other. In order to keep the backwardly overhanging ends of each web from interfering with each other, there is provided a usual second guide-bar 53 parallel to and back of the one mentioned above to individually support the upper web at the rear, and which is carried by arms 54 ranging rearwardly from the rear end of the carbon-carriage track, said guide-bar 53 also being provided with settable gages 55 to laterally guide the paper. Additional side gages of known construction are setably arranged upon the lower as well as the upper carbon-carrier at the rear thereof and may be clearly seen from Figure 3, each one including a slotted gage-member 56 fastened to the carrier by thumb-screw 57.

A preferred construction provides means to prevent the blades of the upper carrier from falling off when the carrier, in its Figure 2 position, is turned upwardly and backwardly beyond the vertical line, said means including a flat member or blade 58 at either side, which is pivoted upon the uppermost step of said upper carrier by screw 59, and which is formed to closely cover the finger-pieces 38 of the carbon-blades 36^a when set transversely of the blades to hold the same in place. Figure 3 shows this blade-securing member as being swung sideways to free the finger-pieces for blade-detachment, while, in conjunction therewith, a detail in Figure 5 shows a spring-washer 60 effective to frictionally hold said blade-securing member in any desired position.

Variations may be resorted to within the scope of the invention, and portions of the improvements may be used without others.

Having thus described my invention, I claim:

1. In a continuous-billing typewriting machine having a revoluble platen journaled in a platen-frame, to alternately feed one of two superposed multiple-ply-webs, while the other one is idling upon the machine, the web-plies being interleaved with carbons to be shifted periodically between the plies for use in consecutive sections thereof, a reciprocating carriage back of the platen and mounted upon an extension of the platen-frame for traveling movement in the line of web-feed, a set or unit of blade-like holders mounted upon steps of said carriage and edgewise adjacent to each other, each of said blades controlling the rear end of a carbon to periodically shift the same between the plies of the lower of the work-webs, a unit of carbon-blades to accommodate the upper work-web, substantially as a duplicate superposed upon the first-mentioned unit and hinged thereto at the rear so as to enable the upper unit to be swung out of the way rearwardly to facilitate handling and mounting of the lower web when the upper web is idle,

and means to determine extreme tilting positions of the upper unit. 65

2. In a continuous-billing typewriting machine having a revoluble platen journaled in a platen-frame, to alternately feed one of two superposed multiple-ply-webs, while the other one is idling upon the machine, the web-plies being interleaved with carbons to be shifted periodically between the plies for use in consecutive sections thereof, the combination of carbon-controlling means, said means including a set of holding blades carrying the rear ends of the carbons for the lower web, said blades by means of pin-and-hole connections mounted upon steps which form a lower blade-carrier reciprocatively movable in the line of paper-feed upon a rearward extension of the platen-frame, an upper blade-carrier substantially a duplicate of the lower one, to accommodate the upper multiple-ply-web, said upper carrier at the rear end hinged to the lower one and swingable rearwardly beyond the vertical when the web thereon is idle, so as to facilitate handling and mounting of the lower web, settable means to hold the blades seated upon the upper carrier when the same is turned over to rearward position, and means to determine the forward and rearward position of said upper carrier. 85

3. In a continuous-billing typewriting machine having a revoluble platen journaled in a platen-frame, to alternately feed one of two superposed multiple-ply-webs, while the other one is idling upon the machine, the web-plies being interleaved with carbons to be shifted periodically between the plies for use in consecutive sections thereof, the combination of carbon-controlling means, said means including a set of holding blades carrying the rear ends of the carbons for the lower web, said blades by means of pin-and-hole connections mounted upon steps which form a lower blade-carrier reciprocatively movable in the line of paper-feed upon a rearward extension of the platen-frame, an upper blade-carrier substantially a duplicate of the lower one, to accommodate the upper multiple-ply-web, said upper carrier at the rear end hinged to the lower one and swingable rearwardly beyond the vertical when the web thereon is idle, so as to facilitate handling and mounting of the lower web, settable hold-down members to secure the blades in place upon the upper carrier when the latter is turned over to rearward position, said members extending transversely of the blades to hold down the fixed ends thereof, and means to determine the forward and rearward position of the upper carrier. 100

4. In a continuous-billing typewriting machine having a revoluble platen journaled in a platen-frame, to alternately feed one of two superposed multiple-ply-webs, while the

other one is idling upon the machine, the web-plies being interleaved with carbons to be shifted periodically between the plies for use in consecutive sections thereof, the combination of carbon-controlling means, said means including a set of holding blades carrying the rear ends of the carbons for the lower web, said blades by means of pin-and-hole connections mounted upon steps which 10 form a blade-carrier reciprocatively movable in the line of paper-feed upon a rearward extension of the platen-frame, an upper blade-carrier substantially a duplicate of the lower one, to accommodate the upper

multiple-ply-web, said upper carrier at the 15 rear end hinged to the lower one and swingable rearwardly beyond the vertical when the web thereon is idle, so as to facilitate handling and mounting of the lower web, a flat member settable mounted upon the 20 upper carrier to hold the blades thereon in place when the carrier is turned over to rearward position, said flat member normally extending across the fixed ends of said carbon-blades but swingable to free the same, 25 and means to determine the forward and rearward position of the upper carrier.

GEORGE W. RENZ.
